Samuel F. Pratt, of Boston, Mass. - Assign to
Breadwell, Perry & Norton, of Albany, N.Y.
Letters Patent No. 864. Dated, Jan. 13, 1837

The Schedule referred to in these Letters Patent
and making part of the same.

To whom it may concern.

Be it known that S. Samuel F. Pratt of the City of Boston, State of Massachusetts have produced a new ornamental design for the plates of a Parlour Stove, named by me the Violet; and I hereby declare that the annexed drawings forming part of this specification are full and accurate delineations of the said plates forming part of the said stove.

What I claim, and desire to secure by Letters Patent, is the combination and arrangement of ornamental figures and forms represented in the accompanying drawings, forming the plates, being part of the above described stove.

Signed at Boston, this twenty seventh day of October
A.D. 1836.
